ARTHUR H. SWEETLAND, OF LONG BEACH, CALIFORNIA, ASSIGNOR TO NATIONAL STREET AND STATION INDICATOR COMPANY, OF LOS ANGELES, CALIFORNIA, A CORPORATION OF CALIFORNIA.

TRACK-CONTROLLED MECHANISM.

1,117,722.

Specification of Letters Patent.

Patented Nov. 17, 1914.

Application filed December 15, 1913. Serial No. 806,913.

To all whom it may concern:

Be it known that I, ARTHUR H. SWEETLAND, a citizen of the United States, residing at Long Beach, in the county of Los Angeles, State of California, have invented new and useful Improvements in Track-Controlled Mechanisms, of which the following is a specification.

This invention relates to improvements in track controlled switches, and particularly to improvements in devices of the character shown by Edgar J. Pace in his application, Serial Number 697,439 filed Dec. 23rd, 1911 and 735,934 filed September 16th, 1913; and the improvement of this present application has to do with rendering the apparatus more positive and accurate and reliable in its operation.

In the application first mentioned above, there is described a combination including a stationary magnetic conducting track plate, and a movable system including a source of magnetism and a magnetically actuatable mechanism spaced apart and movable together over the track plate; in the second mentioned application, the magnets are duplicated and placed one on each side of the magnetically actuatable mechanism (preferably in the form of a magnetically movable needle), so that the device will operate with equal efficiency in opposite directions of motion.

The present application has to do with improvements on both of the prior mechanisms, the present mechanism having equal efficiency of action in both of the opposite directions of movement; and one of the prime objects of the present invention is the provision of the apparatus in such form that it will not be actuated by any magnetic conductors other than those designed especially for the purpose. For instance, it has been found to be more or less difficult to prevent a switch track rail from causing the actuation of the forms shown in the prior applications, especially if the switch track makes a very acute angle with the main track.

My present form of apparatus entirely obviates the possibility of undesired actuation, mainly by providing two magnetic conductors through which the magnetic flux must pass in series in order to have full effect upon the magnetically actuatable mecha-

nism. These conductors are so placed with relation to each other and with relation to the movable parts of the mechanism that it is impossible for their magnetic effects to be duplicated by any cross over switch, crossing track rails or the like.

I describe preferred forms of my improved mechanism in the following specification, said forms being illustrated in the accompanying drawings, in which,

Figure 1 is a perspective illustrating the essentials of my improved mechanism, Fig. 2 is a partial plan of the movable parts of the mechanism, Fig. 3 is a perspective showing a modified form of device.

In the drawings the numeral 10 may designate any track construction upon which I place two preferably parallel spaced magnetic conducting bars 11. These bars will preferably be placed longitudinally of the track; although this is not necessarily the case. The movable element of the mechanism is carried in any convenient manner on a car or the like; and includes preferably a pair of magnets 12 (preferably electromagnets) spaced horizontally apart from each other and lying in a horizontal plane above the bars 11. The magnetic poles of each magnet 12 are spaced horizontally apart from each other and are preferably above the respective bars 11, like poles being directly above the same bars. The magnets 12 are mounted in any suitable framework 13 and preferably have depending pole pieces 14, pivoted on suitable studs 15. Preferably I insert ball bearings 16 between the pole pieces 14 and the cores 19 of the magnets so as to prevent excessive friction between the cores and the pole pieces. The pole pieces swing about their pivotal supports so that they will not be damaged by striking any object upon the track. Their lower ends preferably approach to within an inch or two of the magnetic bars 11. When the magnets come over the bars 11, in the relative position shown in Fig. 1, there is an induced magnetism in the bars 11, forming consequent poles about midway between the two magnets in each of the bars. A consequent south pole will be formed in the middle portion of one of the bars while a consequent north pole will be formed in the opposite section of the other bar.

Situated midway between the two mag-

nets 12 and mounted on the framing 15, is a magnetically actuatable mechanism 20, preferably including a pair of pole blocks 21 and a rotatable vane or armature 22 mounted on a vertical axis 23 in the opening between the two pole blocks. Mounting the vane on a vertical axis entirely obviates all effects of gravitation tending to rotate the armature; the armature does not have to be so nicely balanced as it does when mounted on a horizontal axis. In Fig. 2 I have shown the mechanical construction for the mounting and operation of the armature. The shaft 23 is mounted in suitable bearing plates 24, and a small spiral spring 25 tends to normally hold the shaft and armature in the position shown in Figs. 1 and 2, there being slight tension on the spring 25 in this position. A small stop 26 prevents the armature 22 from moving too far in the direction opposite to that indicated by the arrow; so that the armature, composed of a piece of magnetic material, is always in a position to be attracted in the direction indicated when the pole blocks 21 are magnetized. The vane or armature may be a magnet of any form or merely a piece of magnetic material. The shaft 23, by its rotation may operate any desired form of switch, such as a switch 30 whose movable arm 31 is actuated by a small cam 32 on the shaft 23. The pole blocks 21 have pole pieces 33 pivoted on studs 34 hanging below the pole blocks with their lower ends above the plane of the track plates or bars 11.

The magnets 12, whether permanent or electro-magnets, are constantly energized, so that the pole pieces 16 normally have polarities as indicated. When the movable element of the mechanism passes over the stationary bars 11, there are two independent and separate circuits set up, one from each magnet 12 through the bars 11 through the pole pieces 31 and through the magnetically actuatable mechanism 20. It will be seen that the mechanism will operate if there be only one magnet 12; but the provision of two magnets one on each side of the mechanism 20 provides that the whole device shall be symmetrical with relation to the mechanism 20 and therefore that it shall actuate with equal efficiency in either direction of movement. It is preferred that the movable element of the device move in the directions indicated by the arrows in Fig. 1 with reference to the bars 11; but it is not impossible that the movable elements have a movement in the horizontal plane at right angles to the direction indicated. It is only necessary that, during the movement of the movable element, it is brought over the bars in the relation shown in Fig. 1, so that there may be a magnetic flow from one or both magnets 12 through both the track conductors 11 to the mechanism 20. Considering now

only one of the magnets 12, it will be seen that the magnetic flow passes in series through the two bars 11; that the absence of either of the bars will create a gap equal to the distance between the magnet and the mechanism 20 and will thereby greatly diminish the amount of magnetism supplied to the mechanism. In practice I make the dimensions of the magnetic circuit so that the removal of one of the bars 11 will cause a reduction of the respective magnetism in the mechanism 20 to about one-fourth or one-fifth of its value when both bars 11 are in place. That is, the reluctance of the magnetic circuit using only one of the bars 11 is perhaps four or five times the reluctance using both the bars. Considering the system including two magnets 12, it is seen to be necessary to so place and arrange the magnets that their like poles will come over one or the other of the bars 11; if the arrangement were otherwise, there would be a simple closed magnetic circuit through the magnets 12, their pole pieces 16 and the bars 11, without including the mechanism 20 at all in the magnetic circuit.

With the arrangement as shown in the drawings, if the device passes over a rail or other object which may more or less simulate one of the bars 11, there will not be sufficient magnetism supplied to the mechanism 20 to cause its operation. While it is likely that the movable element of the device may pass over one such member which will simulate the action of one bar 11, it is hardly possible that it would simultaneously pass over two such members. It is very likely that the device will pass over a diagonal rail; and such a diagonal rail may simulate the action of one of the bars 11 but could never simulate the action of both the bars 11. If the rail is placed at a sufficient angle with the track, or with the motion of the movable element of the device, its action would be to cause closure of the magnetic circuit between a south pole of one magnet and a north pole of the other magnet. This would tend to simply make a closed circuit between the two magnets and would not have any effect whatever upon the mechanism 20.

I have described my device including the double magnet double track plate arrangement and including a magnetically operable mechanism preferably having a movable vane or needle. The essentials of my invention are answered by the use, in combination, of any magnetically operable mechanism. Thus, as shown in Fig. 3, I may use an inductive device 20^a consisting preferably of a core 21^a and a winding 22^a. The changes in magnetic flux in the core (preferably soft iron) cause induced currents in the winding 22^a, which currents may be used for any desired purpose. The magnetic action

of the device (which action is the principal feature of my invention) remains the same as before described.

I claim—

5. 1. In combination, a magnet and a magnetically actuable mechanism spaced apart so that the magnet normally has no effect on the mechanism, and means for conducting magnetism from the magnet to the mechanism including a pair of magnetic conductors, the conductors and the magnet and mechanism being relatively movable and correlated so that when the parts are in proximity a magnetic circuit is set up from the magnet to the mechanism through both the conductors in series. 70
10. 2. In combination, a magnet and a magnetically actuable mechanism spaced apart and movable together with reference to a track, the magnet having its poles spaced horizontally and the mechanism having similarly spaced pole pieces, and a pair of stationary magnetic conductors on the track spaced apart a distance corresponding to the distance between the poles of the magnet. 75
15. 3. In combination, a magnet and a magnetically actuable mechanism spaced apart and movable together with reference to a track, the magnet having its poles spaced horizontally and the mechanism having similarly spaced pole pieces, and a pair of stationary magnetic conductors on the track spaced apart parallel to each other a distance corresponding to the distance between the poles of the magnet. 80
20. 4. In combination, a pair of parallel spaced magnetic conducting bars, a magnet and a magnetically actuable mechanism spaced apart from each other and movable over the bars, the magnet having pole pieces adapted to move one over each bar and the mechanism having pole pieces arranged in such relation as to be one above each bar at the same time the magnet pole pieces are above the bars. 85
25. 5. In combination, a stationary pair of spaced magnetic conducting bars, a movable system including a pair of substantially parallel magnets with like poles at the corresponding ends of the magnets, and a magnetically actuable mechanism spaced between the magnets, two pole pieces for the mechanism, the pole pieces and the poles of the magnets being respectively spaced apart a distance corresponding to the spacing of the magnetic conducting bars, the magnets and pole pieces and bars being so correlated that when like poles of the magnets and one pole piece of the mechanism are in proximity to one of the bars the other like poles and the other pole piece are in proximity to the other bar. 90
30. 6. In combination, a stationary pair of parallel horizontal spaced bars of magnetic conducting properties, a movable system including a pair of horizontal magnets extending transversely above the bars and spaced apart longitudinally of the bars, a pole piece dependent from each end of each magnet in the vertical planes of the bars, the magnets being arranged with like poles over one bar, a magnetically actuable mechanism between the two magnets, and pole pieces dependent from the mechanism one in the vertical plane of each bar. 95
35. 7. In combination, a stationary pair of parallel horizontal spaced bars of magnetic conducting properties, a movable system including a pair of horizontal magnets extending transversely above the bars and spaced apart longitudinally of the bars, a pole piece dependent from each end of each magnet in the vertical planes of the bars, the magnets being arranged with like poles over one bar, a magnetically actuable mechanism between the two magnets, including a pair of pole blocks, a rotatable armature between the pole blocks, and pole pieces dependent from the pole blocks one in the vertical plane of each bar. 100
40. 8. In combination, two separate and distinct sources of magnetism spaced apart from each other, a magnetically actuable mechanism between the two sources, and a pair of spaced magnetic conductors, the said sources and mechanism being movable relative to the conductors into and out of proximity thereto. 105
45. 9. In combination, a pair of magnets spaced apart horizontally, a magnetically movable needle between the magnets, and a pair of parallel horizontal spaced magnetic conductors, the magnets and needle being movable relative to the conductors into and out of proximity thereto. 110
50. 10. In combination, a magnet and a mechanism capable of being affected by magnetism spaced apart so that the magnet normally has no effect on the mechanism, and means for conducting magnetism from the magnet to the mechanism including a pair of magnetic conductors, the conductor and the magnet and mechanism being relatively movable and correlated so that when the parts are in proximity a magnetic circuit is set up from the magnet to the mechanism through both the conductors in series. 115
55. 11. In combination, a magnet and a magnetically affectable mechanism spaced apart and movable together with reference to a track, the magnet having its poles spaced horizontally and the mechanism having similarly spaced pole pieces, and a pair of stationary magnetic conductors on the track spaced apart a distance corresponding to the distance between the poles of the magnet. 120
60. 12. In combination, a pair of spaced magnetic conductors, and a mechanism coöperating with said conductors, said mechanism and conductors being movable with relation 125

to each other, said mechanism including a magnet with pole pieces spaced apart a distance corresponding to the spacing between said conductors and including also a magnetically actuable mechanism spaced from the magnet and having pole pieces spaced apart corresponding to the spacing between said conductors.

13. In combination, a pair of elongate 10 magnetic conductor bars spaced apart transversely, and a mechanism coöperating with said conductor bars, said bars and said mechanism being movable relative to each other, said mechanism including a magnet 15 extending in a direction transversely across the bars and having pole pieces spaced apart corresponding to the spacing between the bars and including a magnetically actuable mechanism spaced from the magnet in a direction longitudinal of the bars and having 20 pole pieces spaced in a direction transverse of the bars a distance corresponding to the transverse spacing of the bars.

14. In combination, a pair of spaced magnetic conductors, and a mechanism coöperating with said conductors, said mechanism and conductors being movable with relation to each other, said mechanism including a pair of magnetically charged poles of opposite 25 site polarity spaced apart a distance corresponding to the transverse spacing of the magnetic conductors, and including also a magnetically actuable mechanism spaced from said poles and having pole pieces 30 spaced apart corresponding to the spacing between said conductors.

15. In combination, a pair of elongate magnetic conductor bars spaced apart transversely, and a mechanism coöperating with 40 said conductor bars, said bars and mechanism being movable relatively to each other,

said mechanism including a magnet extending transversely across the bars, pole pieces for the magnet spaced apart a distance corresponding to the transverse spacing of the 45 bars, and including a magnetically actuable mechanism spaced from said magnet longitudinally of the bars, said magnetically actuable mechanism including a pair of pole pieces spaced apart transversely of the bars 50 a distance corresponding to the transverse spacing of the bars and a pivoted magnetic member arranged between the pole pieces and adapted to be attracted thereby.

16. In combination, a pair of elongate 55 magnetic conductor bars spaced apart transversely, and a mechanism adapted to coöperate with said bars, said mechanism and said bars being movable relatively to each other, said mechanism including a pair of 60 magnets extending transversely of the bars and spaced apart from each other longitudinally of the bars, pole pieces for each of the magnets, those of each magnet being spaced apart a distance corresponding to the transverse spacing between the bars, like poles 65 of the magnets being arranged adjacent one bar, and a magnetically actuable mechanism arranged between said magnets and including a pair of pole pieces spaced transversely 70 apart a distance corresponding to the transverse spacing between the bars, and a pivoted magnetic needle between the pole pieces and adapted to be attracted thereby.

In witness that I claim the foregoing I 75 have hereunto subscribed my name this 4th day of December 1913.

ARTHUR H. SWEETLAND.
